UNITED STATES PATENT OFFICE.

ANTOINE LACROIX, JR., OF BROOKLYN, ASSIGNOR TO THE CO-OPERATIVE BUILDING PLAN ASSOCIATION, OF NEW YORK, N. Y.

DESIGN FOR THE EXTERIOR OF A COUNTRY HOUSE.

SPECIFICATION forming part of Design No. 19,873, dated October 22, 1889.

Application filed September 28, 1889. Serial No. 326,456. Term of patent 9½ years.

To all whom it may concern:

Be it known that I, ANTOINE LACROIX, Jr., of the city of Brooklyn, in the county of Kings and State of New York, have invented and 5 produced a new and original Design for the Exterior of a Country House, of which the following is a specification, reference being had to the accompanying drawings, forming a part thereof.

10 Figure 1 represents a perspective view of a country house showing my design. Fig. 2 represents a horizontal section or plan of the first story. Fig. 3 represents a horizontal section or plan of the second story.

15 Similar letters of reference designate corresponding parts in all the figures.

A house of this design consists of two stories, with an attic third story within a gable roof, the first and second stories having a 20 polygonal bay on either side of the house, and the said bay being surmounted by a balcony of corresponding plan, within which is a dormer, and the said balcony and dormer being covered by a roof which is partly gabled and 25 partly pyramidal, part of the front and one side of the first story being included within a piazza, all as hereinafter more particularly described in detail with reference to the drawings.

30 A B C designate the front of the house, in which the first and second stories are of the same width and the third is included within the gable of the roof. From the ground to the top of the second story, about half the width 35 of the front, the wall is flat, and the remainder of the width is a bay A' B', which is in the form of three sides of a polygon and which has a pyramidal roof C', one side of which

abuts against the gable C. The side walls D 40, which extend from the ground to the top of the second story, are straight, except there is in each an octagonal bay E running up through both stories about midway between the front and back, the said bays being of polygonal form, as shown in Figs. 2 and 3. 45 Above this bay, and projecting from the side of the gable roof G, is a balcony E', which conforms in plan to the bay E, and within this balcony there is a dormer projection F from the roof, which projection is quadrangular in plan. The roof H, which covers the said dormer F and balcony E', is of gabled form, projecting from the main roof G, and finished in front in pyramidal form to conform in plan to the balcony E' and the bay E. 55

The first story has a rectangular rear extension I (see Fig. 2) about half the width of the house, and this extension has a hipped roof J.

L designates a piazza of L shape, which runs along the front of the flat portion A of the first story and a portion of the adjacent side D, extending so far along the front as to include the first panel of the bay A' and along the side to include the first panel of the bay E on that side. This piazza has a shed roof M, from the front of which projects a gable N, forming a porch over the stoop O.

What I claim is—

The design for the exterior of a country house, substantially as herein shown and described.

ANTOINE LACROIX, JR.
